UNITED STATES PATENT OFFICE

160,045

UNDERSEA SALVAGING VESSEL

Walter Wiggins, Jr., Washington, D. C.

Application January 30, 1950, Serial No. 7,575

Term of patent 14 years

(Cl. D71—1)

To all whom it may concern:

Be it known that I, Walter Wiggins, Jr., a citizen of the United States, residing at Washington, in the District of Columbia, have invented a new, original, and ornamental Design for an Undersea Salvaging Vessel, of which the following is a specification, reference being had to the accompanying drawings, forming part thereof.

Figure 1 is a top plan view of an undersea salvaging vessel, showing my new design;

Figure 2 is a side elevational view thereof;

Figure 3 is a bottom plan view;

Figure 4 is a front elevational view; and

Figure 5 is a transverse sectional view, taken substantially in the plane of the line 5—5 in Figure 1.

I claim:

The ornamental design for an undersea salvaging vessel, as shown.

WALTER WIGGINS, JR.
